UNITED STATES PATENT OFFICE.

HARRY C. MALLORY, OF NEW YORK, N. Y.

STEAM GENERATION AND UTILIZATION.

1,236,854.

Specification of Letters Patent. Patented Aug. 14, 1917.

Application filed September 6, 1907, Serial No. 391,581. Renewed January 10, 1917. Serial No. 141,696.

To all whom it may concern:

Be it known that I, HARRY C. MALLORY, a citizen of the United States of America, residing in the city, county, and State of New York, have invented a certain new and useful Improvement in Steam Generation and Utilization, of which the following is a true and exact description, reference being had to the accompanying drawings, which form 10 a part thereof.

The object of the present invention is the provision of simple and effective apparatus by which the fuel supply of a fluid fuel burning steam generator, particularly of the 15 flash boiler or semi-flash boiler type, is automatically regulated in accordance with the demand for steam whether the latter be used for power or heating purposes, and

An advantageous utilization of this automatically regulated steam generator in a heating system in which the steam flow through the radiator is varied to vary the heating effect of the radiators, the system being so arranged that the steam supplied 25 to the radiators is returned to the steam generator in the form of water of condensation.

In carrying out my invention, I have devised an apparatus in which the valve which 30 regulates the flow of the fluid fuel to the burner or burners of the steam generator is controlled by a thermostatic mechanism which is subjected on the one hand to the cooling action of the water fed to the boiler to be 35 converted into steam and on the other hand to the heating action of some source of heat of a temperature which is relatively constant and materially higher than that of the water of condensation, thus obtaining a range of 40 temperature to which the thermostatic mechanism is subjected which is sufficient to make the action of the latter positive and of sufficient extent to give the desired regulation.

By preference, I utilize the pilot burner 45 employed to start the main burner when fuel begins to flow to it after a temporary cessation as the source of the heat of high temperature.

The supply of water to the boiler I may 50 regulate by means of a valve or the like actuated or controlled by the steam pressure in the steam main from the boiler, and in one form of my invention I have provided for a regulation which insures that the steam

shall not only be as great as desired but shall 55 be superheated as much as thought necessary.

When my new steam generator is employed in a heating system in which the escape of water of condensation from the radiators is automatically controlled in order 60 to govern the heating effect of the radiator I may arrange for a direct return of the water of condensation to the boiler, as by gravity flow. In this case the water of condensation forms a direct measure of the 65 steam consumption and of the steam generated and automatically controls the supply of heat for its conversion into steam.

The various features of novelty which characterize my invention I have aimed to 70 point out particularly in the claims annexed to and forming a part of this specification. For a better understanding of my invention, however, and the advantages possessed by it reference may be had to the accompanying 75 drawings and descriptive matter in which I have illustrated and described several forms of apparatus in which my invention may be embodied.

Of the drawings,

Figure 1 is a somewhat diagrammatic elevation, partly in section, showing a steam generator and automatic fuel controlling mechanism therefor and one means for regulating the flow of water to said generator in 85 order to maintain the steam pressure at the desired point.

Fig. 2 is an elevation showing a device which may be used with the apparatus shown in Fig. 1 when it is desired to regulate the 90 degree of superheat as well as the pressure of the steam produced by the generator.

Figs. 3 and 4 are sectional elevations, each showing a valve employed in Fig. 1 in regulating the flow of water to the boiler.

Fig. 5 is a diagrammatic representation of a heating system in which the apparatus of Fig. 1 is utilized, and

Fig. 6 is a diagrammatic representation of a heating system differing somewhat from 100 that shown in Fig. 5, and in which also the steam generator proper of Fig. 1 is utilized.

In the drawings, and referring first to the construction shown in Fig. 1, A is the steam generator, which may be any of the well 105 known forms of flash or semi-flash boilers, and, as shown, comprises heating coils A' to the upper end of which water is supplied

by a pipe A^1 , and from the lower ends of which steam issues through the main steam pipe A^6 . The coils A' are inclosed in a suitable casing A^2 from the upper end of which the chimney or pipe A^9 leads.

Secured to the side of the casing A^2 is the tubular casing member B of the thermostatic fuel control mechanism. The member B has secured to its upper end a chambered member B' , and to its lower end a valve casing C .

10 The valve casing C is provided with a partition C' which divides the fuel chamber C^2 from the water chamber C^3 . The fuel passes into the fuel chamber C^2 from the

15 fuel supply reservoir E through the pipes E' and C' , and the valve seated port C^4 formed in the member C^5 , which is detachably connected to and forms a part of the valve casing. The flow of fuel, which may

20 be gasoline, gas or other fluid fuel, from the fuel supply reservoir E into the fuel chamber C^2 is controlled by the valve D which is adapted to seat on the member C^5 and close the port C^4 . From the fuel chamber

25 the fuel passes through the pipe A^5 to the main fuel burner A^3 , which serves as the source of heat for converting into steam the water fed into the heating coils A' . A branch pipe E^2 connected to the pipe E'

30 supplies fuel to the pilot burner A^4 , which may be of the usual type employed with a main burner, whenever the fuel supply to the latter is interrupted from time to time. The valve D is carried by and may form the

35 lower end of a hollow member B^2 , which passes through a stuffing box C^6 formed in the partition C' , and is adjustably secured at its upper end to the casing or chambered member B' . In the form shown the upper

40 end of the rod B^2 is threaded and screws into a nut B^9 which normally rests on a boss B^8 extending upward from the lower wall of the chamber in the casing B' . A dowel pin B^{10} secured in the boss B^8 pre-

45 vents rotation of the nut B^9 on its seat when it is desired to rotate the member B^2 in it; in order to adjust the latter axially, while at the same time this arrangement allows the nut to rise from its seat in case of expansion of the rod B^2 occurring after the valve

50 D is seated. A spring C^8 acting between a collar C^9 on the rod B^2 and a stationary bushing C^{10} urges the rod B^2 at all times in the direction to seat the valve D .

55 The rod B^2 is surrounded by a tubular shell B' , which extends between the casings C and B' , and the space B^6 between the rod B^2 and the member B' forms a channel for conveying the water fed into the water

60 chamber C^3 of the casing C from the supply pipe A^8 up into the chamber in the member B' , from whence it passes through the pipe A^7 to the coils A' . Ports B^{11} are formed in the boss B^8 through which the water may

65 pass into the chamber in member B' . As

shown, there is a space B^5 annular in cross section between the member B and the member B' . This space is connected at its upper end to the interior of the casing A^2 by the hollow connection B^4 , and at its lower end 70 by the pipe B^3 . The pipe B^3 , which projects through the casing wall A^2 , is downwardly curved and extends over the pilot burner A^4 so that the gaseous product of combustion from the latter passes into the pipe B^3 and 75 thence through the space B^5 between the members B and B' to the connection B^4 , through which it escapes to the upper end of the casing A^2 . The member B , which serves to positively connect the chambered member 80 B' and the valve casing C , is formed of material having a relatively low co-efficient of thermal expansion, while the rod B^2 , which forms the expanding member of the thermostatic mechanism, is formed of some 85 material having a relatively high co-efficient of thermal expansion.

When the apparatus just described is in operation, the hot gases from the burner A^4 heat the member B' , and thus by radiation 90 and conduction through the water in the space B^6 between the member B' and the rod B^2 tends to heat the latter. When the water in the space B^6 is stationary, the heating action of the member B' on the rod 95 B^2 is sufficient to cause the latter to expand and move the valve D onto its seat, thus cutting off the supply of fuel to the burner A^3 . When, on the other hand, the conditions are such that water is flowing through the space 100 B^6 into the heating coils of the steam generator, the temperature of the rod B^2 will be more or less lowered by such water, with a consequent contraction of the member B^2 . The amount of this contraction will depend 105 of course upon the rate of flow, and to some extent the temperature of the water through the space B^6 . In practice, the temperature of the water passing through the space B^6 in any given installation will not vary 110 appreciably, and the variation will not be sufficient to affect the regulation of the parts after having once been adjusted for the average water temperature. The valve D is a throttling valve arranged to regulate the 115 flow of the fuel in accordance with the degree of contraction or expansion of the member B^2 , so that the fuel supply to the burner A^3 will at all times vary in substantial accordance with the amount of water fed to 120 the coils A' . It should be understood that the parts are proportioned and adjusted so that the fuel fed to the burner A^3 is at all times sufficient to vaporize the water then being fed to the boiler.

125 In the particular form of the apparatus shown in Fig. 1, water is pumped into the water chamber of the valve casing C through the pipe A^8 by the steam pump F , which is supplied with steam from the main steam 130

supply pipe A⁶ through the pipe A¹³, and exhausts steam through the pipe F'. The pump draws water from a suitable source through the pipes F² and F³, and discharges water 5 through the pipe F⁴, which is connected to pipe A⁸. Between pipes F³ and F⁴ is located a by-pass valve J, which has its inlet and outlet ports J' and J² separated by interior valve seated ports J³ and J⁴, which are controlled by the substantially balanced valve 10 J⁵. The stem J⁶ of the valve J⁵ is connected to a diaphragm J⁷, and is acted upon in the direction to hold the valve J⁵ in the closed position by a spring J⁹, and in the opposite 15 direction to open the ports J³ and J⁴ and connect the pipes F³ and F⁴, by steam admitted to the pressure chamber J⁸ through the pipe A¹⁵ running from the main steam pipe A⁶. In the pipe A⁸ is located a valve 20 casing K having in it the valve seated port K' controlled by the valve K². The valve K² is normally urged against its seat by the spring K⁴, the tension of which is regulated by the abutment screw K⁵ threaded 25 into the casing. The valve K² will close when the pressure in the pipe F⁴ does not exceed that in the pipe A⁸, but upon a predetermined excess of pressure in pipe F⁴ over that in the pipe A⁸ the valve K² is moved 30 off its seat.

In consequence of this arrangement, when the steam pressure in the pipe A⁶ is below a predetermined value the spring J⁹ moves the by-pass valve member J⁵ into position 35 to close the ports J³ and J⁴, and the water drawn into the pump F through the pipes F² and F³ is discharged from the pump through the pipes F⁴ and A⁸ into the water chamber C³ of the casing C, through which 40 it passes as before described into the heating coils A' and is vaporized, thus raising the steam pressure. When, however, the steam pressure in the pipe A⁶ exceeds a predetermined value the pressure in the chamber J⁸ against the diaphragm J⁷ is sufficient 45 to move the valve J⁵ off its seat and open the by-pass between the pipes F³ and F⁴. Under these conditions the valve K² seats itself, and the flow of water through the 50 pipe A⁸ ceases. It will be observed that the valve J⁵ is a throttling valve, and when the steam consumption is a fraction only of the maximum capacity of the generator the valve J⁵ is neither shut tight nor wide open 55 but is open to an extent sufficient to permit the desired amount of water to pass to the generator.

In the modification of the apparatus of Fig. 1 shown in Fig. 2, a thermostatically controlled valve N⁵ is located in the pipe A¹⁵ of the by-pass valve controlling mechanism. The actuating mechanism for the valve N⁵ comprises a thermostat having a hollow expanding member N' inserted in 60 the pipe A⁶. The member N' has secured to

its inner end a non-expanding member N², which through a lever N³ operates the stem N⁴ of the valve N⁵, the arrangement being such that the valve N⁵ is open when the temperature of the steam in the pipe A⁶ is 70 above a predetermined amount, and is closed when the temperature is below a predetermined amount. In consequence, the by-pass is opened only when the pressure in the pipe A⁶ exceeds a predetermined minimum, and 75 also only when the temperature of the steam exceeds a predetermined minimum. By a suitable proportion of the parts this arrangement can be made to insure that the temperature of the steam shall at all times be 80 not less than that corresponding to any desired degree of superheat. The apparatus shown in Figs. 1 and 2 is suitable for use generally where there is a variable demand for steam. In particular it is adapted for 85 use in connection with steam automobiles and in steam heating systems.

In Fig. 5, the apparatus of Fig. 1 is shown in use in a heating system employing one or more heat radiating devices or radiators 90 L for heating apartments or the like. By preference these radiators are of the type in which the heating effect is regulated by controlling the accumulation of water of condensation in them, as in my prior Patent 95 No. 802,766, and in which the escape of the water of condensation is automatically controlled by a thermostatically actuated valve mechanism L², as in my prior Patent No. 851,363. In the system shown in Fig. 5, each 100 thermally actuated valve L² has its outlet pipe L⁵ connected to a pipe I² running to the vacuum or low pressure pump I. The operation of the thermostatic valve L², as in my said Patent No. 851,363, may be controlled jointly 105 through the heating action of the adjacent radiator and the cooling action of the stream of air drawn through the valve mechanism L² into the pipe L⁵ and varied in amount by the pilot thermostatic valve L⁸. 110

The pump I discharges through a pipe I³ into the receiving tank H, from which water is drawn by the steam pump F through the pipe F². The pipe I² is connected by a pipe I⁴ and valve I⁵ to a condenser G so 115 that the pump I may pump air from the condenser when necessary. The receiving tank H is provided with an air escape vent H', and tank H is also connected to the condenser G through pipe G' and valve G² so 120 that water may flow from the condenser into the receiving tank. The steam pump I is operated by steam supplied from the main steam pipe A⁶ through pipe A¹⁴, and the steam exhaust pipe I' of the pump is connected to the steam supply pipe L⁴ of the radiator, as is also steam exhaust pipe F' of the steam pump F. The pipe F⁵ and valve F⁶ form a connection between the steam exhaust pipes F' and I' and the con- 125 130

4

denser G to permit any excess of steam from the pipes F' and I' over that required by the radiators to pass into the condenser. It will thus be observed that the radiator L is supplied with steam from the exhaust pipes of the pumps F' and I'. Any excess of steam required by the radiators over that furnished by the exhaust pipes may be supplied through the pipe connection A¹⁰ between the pipe L⁴ and the main steam pipe A⁶. The pipe connection A¹⁰ includes a pressure reducing valve A¹¹ which is arranged to reduce the high pressure steam in the main steam pipe A⁶ to the desired value for use in the heating system. Where the steam generated by the boiler A is intended to be utilized in the heating system proper, practically all of the steam generated by the boiler is returned to it through the tank H, but where the steam pipe A supplies steam to other steam consuming devices this may not be the case. If the other steam consuming devices are connected to condensers the water of condensation may be returned to the reservoir H through the valved connection H². In any event, the usual provision should be made for supplying water to the system to compensate for the unavoidable losses through leaky fittings and the like.

In the heating system shown in Fig. 6, the steam pipe A⁶ supplies steam directly to the heat radiating supply pipe or pipes L⁴ of one or more heat radiators, and the outlet pipe or pipes L⁵ of the radiators lead directly to a tank H³ in which a low pressure is maintained by means of the vacuum pump M, which, in the form shown, is driven by an engine of the internal combustion type supplied with fuel from the fuel tank E through the pipe M'. The receiving tank H³ is preferably arranged above the boiler A so that the water will flow from the receiving tank H³ directly into the pipe A⁸, passing from thence into the steam generator A. In this system it will be understood that the steam pressure is relatively small and will not exceed the difference in water head between the casing B⁷ and the receiving tank H³, while in the apparatus of Figs. 1 and 5 the steam pressure generated by the boiler may be high, say four hundred or five hundred or more pounds per square inch.

The heating system shown in Fig. 6 is much simpler than that shown in Fig. 5, and I prefer it to that shown in Fig. 5 where the steam generator is used solely as a means of supplying steam to heat radiating devices of the character shown.

In the system shown in Fig. 6 the supply of fuel to the main burner A³ is of course regulated by the amount of water passing into the generator; at the same time the amount of water passing into the generator

at any instant is directly equal to the amount of water of condensation escaping from the radiator or radiators at that time, and consequently is directly equal to the demand for fresh steam at that time.

It is my intention to claim in a separate application certain features of novelty relating to the boiler and the means for regulating and controlling the fluid heated in the boiler and the flow of fuel to the burner therefor which are disclosed but not claimed herein.

Having now described my invention, what I claim as new and desire to secure by Letters Patent is:

1. In a steam heating system, a boiler and a radiator, connections for conveying steam from the boiler to the radiator, other connections for conveying water of condensation formed by the steam passing into the radiator back to the boiler, means for controlling the flow of steam through the radiator, and means for automatically regulating the amount of heat supplied to the boiler in response to the volume of the water of condensation passing to the boiler.

2. In a steam heating system, a boiler and a radiator, connections for conveying steam from the boiler to the radiator, other connections for conveying water of condensation formed by the steam passing into the radiator back to the boiler, means for controlling the flow of steam through the radiator, a heater for the boiler, and controlling mechanism therefor, including a thermostatic member thermally acted upon by the water of condensation passing to the boiler and responsive to the volume of such water passing to the boiler.

3. In a steam heating system, a boiler and a radiator, connections for conveying steam from the boiler to the radiator, other connections for conveying water of condensation formed by the steam passing into the radiator back to the boiler, thermostatic means for automatically controlling the flow of steam through the radiator, and means for automatically regulating the amount of heat supplied to the boiler in response to the volume of the water of condensation passing to the boiler.

4. In a steam heating system, a boiler and a radiator, connections for conveying steam from the boiler to the radiator, other connections for conveying water of condensation formed by the steam passing into the radiator back to the boiler, thermostatic means for automatically controlling the flow of steam through the radiator, a heater for the boiler, and controlling mechanism therefor, including a thermostatic member thermally acted upon by the water of condensation passing to the boiler and responsive to the volume of such water passing to the boiler.

5. In a steam heating system, a boiler and a radiator, connections for conveying steam from the boiler to the radiator, other connections for conveying the water of condensation formed by the steam passing into the radiator back to the boiler, a thermostatically actuated valve for automatically regulating the escape of the heating fluid from the radiator, a fluid fuel burner for heating the boiler, a valve controlling the supply of fuel to the burner, and controlling means for the valve, including a thermostatic member thermally acted upon by the water of condensation passing to the boiler and directly responsive to the volume of such water being passed to the boiler.
6. In a steam heating system, a flash boiler, a radiator having steam inlet and low pressure return pipes, pumping mechanism for maintaining low pressure in the return pipe of the radiator and for returning the water of condensation formed by the steam passed into the radiator back to the boiler, means for supplying steam from the boiler to the pumping mechanism to actuate the latter, means for passing the exhaust steam from the pumping mechanism into the radiator inlet pipe, means responsive to the pressure in the radiator inlet pipe for supplying steam from the boiler directly to the radiator inlet pipe but at a reduced pressure upon a predetermined fall in said pressure in the radiator inlet pipe, means for heating said boiler, and automatic regulating means therefor directly responsive to the volume of such water being returned to said boiler.
7. In a steam heating system, a flash boiler, a radiator, means for conveying steam from the boiler to the radiator, other connections for conveying the water of condensation formed by steam passing into the radiator back to the boiler, means for controlling the flow of steam through the radiator and means for automatically regulating the amount of heat supplied to the boiler, comprising a thermostatic member arranged to be acted upon thermally by the water of condensation passing to the boiler, and means tending to maintain said thermostatic member at a constant temperature above that of the temperature of the water of condensation returning to the boiler.
8. In a steam heating system, a flash boiler, a radiator, connections for conveying steam from the boiler to the radiator, other connections for conveying the water of condensation formed by the steam passing into the radiator back to the boiler, means for controlling the flow of steam through the radiator, a main burner for heating said boiler, a pilot burner, a valve controlling the supply of fuel to the main burner and thermostatic controlling mechanism for said valve, comprising an expansible member arranged to be acted upon thermally by the water of condensation returning to the boiler and to be heated by said pilot burner.
